D. B. SWEENEY.
CONTINUOUS FILTER PRESS,
APPLICATION FILED MAR. 22, 1916.

Patented Jan. 16, 1917.

1,212,844.

UNITED STATES PATENT OFFICE.

DANIEL BERNARD SWEENEY, OF BAYONNE, NEW JERSEY.

CONTINUOUS FILTER-PRESS.

1,212,844.

Specification of Letters Patent.

Patented Jan. 16, 1917.

Application filed March 22, 1916. Serial No. 85,814.

To all whom it may concern:

Be it known that I, DANIEL BERNARD SWEENEY, citizen of the United States of America, residing at Bayonne, Hudson county, State of New Jersey, have invented a new and useful Improvement in Continuous Filter-Presses; and I do hereby declare the following to be a full, clear, and exact description of the same.

10 This invention relates to filters, particularly devices or machines for separating solids or semi-solids from liquids, and more especially to machines for separating wax or other material from oils or by-products of 15 oils.

The object of the invention is to provide a very compact and efficient filter for said purpose, which will be continuous in operation, require little power or space, give a uniform output, be automatic in operation, and which will not easily get out of order. To this end I have provided the continuous filter press hereinafter described, it being particularly pointed out that various 25 changes in the sizes, shapes and details of construction and combination may be made without departing from the spirit and scope of the invention as claimed.

In the accompanying drawing showing, 30 by way of example only one of many possible embodiments of the invention, Figure 1 is a side-elevation of the machine, part being broken away; Fig. 2 is a cross-sectional view shown on a larger scale; Fig. 3 is a fragmental portion of Fig. 2 shown on a still larger scale; and Fig. 4 is a longitudinal sectional view of a detail.

Referring more particularly to the drawing, the filter press is shown provided with 40 a perforated cylindrical casing 5 which may be made up of any convenient number of segments 6, provided with side ribs 7 and end flanges 8 by means of which the sections may be bolted together as shown, or may be 45 hinged or otherwise secured. The casing is provided with perforations 9 and is lined interiorly with suitable canvas or filtering material 10 which is secured at its edges between the ribs 7. Between the canvas and 50 the perforations 9 a wire fabric 11 is disposed. Between the portions of canvas caught between the ribs 7, metallic strips 12 are secured, and project inwardly toward the axis of the casing forming a bearing for 55 the screw conveyer 14 disposed longitudinally of the casing and provided with end

shafts 16 and 17 received in suitable bearings in the closed ends of the casing. The strips 12 serve to support the screw conveyer and hold it a slight distance away from the canvas 10. At the inlet end of the casing, a feed pipe 19 conducts the liquid to be filtered to the interior of the casing. At the outlet end a pipe 20 discharges the wax or liquid-feed material through the adjustable valve 65 21 controlled by a weight 22. The end shaft 17, is continued through a suitable stuffing box 24 to the outside of the casing and is provided with a gear or the like 25 by which power is received for rotating the feed screw 70 in the direction of the arrow of Fig. 2.

The operation of the filter press is as follows:—The oil or liquid to be filtered is fed in through the feed pipe 19 at a suitable pressure, for instance 300 pounds, and immediately begins to pass through the canvas, the wire fabric and out through the perforations 9, leaving the wax on the canvas to be scraped off by the screw conveyer and forced out through the pipe 20 and valve 21. By 80 adjusting the weight 22 the pressure of the discharge may be varied, and the required dryness of the wax attained. The resistance to the rotation of the screw conveyer is greatest at the discharge end, hence the gear 85 25 is placed at that end.

I claim as my invention:—

1. In a filter press, the combination of a cylindrical filter casing; a rotary screw disposed longitudinally of the casing; feed and discharge pipes at opposite ends of the casing; and means engaging said screw at 90 points along the side thereof for holding the screw out of contact with the sides of the casing.

2. In a filter press, the combination of a cylindrical filter casing; a continuous rotary screw disposed longitudinally of the casing; feed and discharge pipes at opposite ends of the casing; and means engaging 100 said screw at points along the side thereof for holding the screw out of contact with the sides of the casing.

3. In a filter press, the combination of a cylindrical filtering casing; a screw conveyer in said casing; feed and discharge pipes at opposite ends of the casing; and means engaging a plurality of points of the screw for holding it out of contact with the casing.

4. In a filter press, the combination of an elongated perforated cylindrical casing; a

- layer of canvas lining the casing; a screw conveyer in the casing; ribs for holding the conveyer from the canvas; means for rotating the conveyer; and a feed pipe and a discharge pipe communicating with opposite ends of the conveyer.
5. In a filter press, the combination of a cylindrical filtering casing; comprising segments; a screw conveyer in said casing; and strips placed between said segments and holding the screw from the sides of the casing.
6. In a filter press, the combination of a cylindrical filtering casing; a screw conveyer therein; and longitudinal ribs inside of the casing for holding the screw conveyer from the sides thereof.
7. In a filter press, the combination of an elongated, perforated cylindrical casing comprising a plurality of segments and closed at both ends; a layer of canvas lining the cylinder; a wire fabric between the canvas and the perforations of the cylinder; metallic strips secured between said segments and projecting a short distance into the cylinder; a screw conveyer journaled in the ends of said casing and centered in said casing by said strips; a feed pipe and a discharge pipe communicating with opposite ends of the casing; a safety valve in said discharge pipe; and means for rotating the conveyer.
8. In a filter press, the combination of a cylindrical casing comprising perforated side segments; a canvas lining for each segment and having its edges secured between the segments; and a screw conveyer in the casing.
9. In a filter press, the combination of a cylindrical casing comprising perforated side segments; a canvas lining for each segment and having its edges secured between the segments; a screw conveyer in the casing; and a wire mesh between each canvas and the adjacent segment.
10. In a filter press, the combination of a cylindrical perforated casing; a canvas lining therein having all of its inner face exposed to fluid in the casing; a wire fabric disposed between the sides of the casing and the canvas for holding the canvas out of contact with the casing and permitting the passage of liquid, between the casing and the canvas, from imperforate portions to the perforations; and means disposed along the sides of the casing for holding said scraping means just out of contact with the filtering sides.
11. In a filter press, the combination of a cylindrical casing having filtering sides; a screw conveyer in said casing; feed and discharge pipes at opposite ends of the casing, said screw having threads shallow enough to prevent the passage of liquid along the bottom of the screw without filtering; and means disposed along the sides of the casing for holding said scraping means just out of contact with the filtering sides.
12. In a filter press, the combination of a cylindrical casing having filtering sides; a screw conveyer in said casing; feed and discharge pipes at opposite ends of the casing, said screw having shallow threads, said threads having a depth approximately one-eighth of the diameter of the screw; and means disposed along the sides of the casing for holding said scraping means just out of contact with the filtering sides.
13. In a filter press, the combination of a cylindrical casing comprising perforated side segments; and end pieces; a canvas lining for each segment having its edges brought between the segments; a wire mesh between each canvas and the adjacent segment; a continuous screw extending approximately from end to end of the casing and having shallow threads having a depth about one-eighth the diameter of the screw and approaching as close as possible to said canvas without touching it; strips placed between the edges of the canvas between the segments and projecting inwardly and holding the screw out of contact with the canvas; feed and discharge pipes at the opposite ends of the casing; and a weighted safety valve in the discharge pipe.
14. In a filter press, the combination of a casing having filtering sides; feed and discharge pipes at opposite ends of the casing; scraping means for feeding material along said sides and scraping it therefrom; and means disposed along the sides of the casing for holding said scraping means just out of contact with the filtering sides.
15. In a filter press, the combination of a casing having filtering sides; feed and discharge pipes at opposite ends of the casing; scraping means for feeding material along said sides and scraping it therefrom; and ribs disposed along the sides of the casing for holding said scraping means just out of contact with the filtering sides.

In testimony whereof, I have signed my name to this specification in the presence of two subscribing witnesses.

DANIEL BERNARD SWEENEY.
